[57] CLAIM

The ornamental design for a playhouse, as shown and described.

DESCRIPTION

FIG. 1 is a perspective view of a playhouse showing my new design;

FIG. 2 is a top plan view thereof;

FIG. 3 is a front elevational view thereof; and

FIG. 4 is a right side elevational view thereof.
The surface texture indicated represents an overall texture within the areas indicated.

The unshown sides of the design are substantially plain and unornamented.

FIG. 1.

FIG. 3.

FIG. 2.

FIG. 4.
